QUICK FREEZE REFRIGERATOR UNIT

Walter S. Phillips, Greensboro, N. C.

Application September 21, 1939, Serial No. 295,970

4 Claims. (CL. 62—126)

This invention relates to a quick-freeze refrigerating unit for use in combination with an ice refrigerator.

The primary object of the invention is to provide a quick-freeze unit in which food may be stored and in which the temperature is maintained at an extremely low level.

Another object is to provide an evaporator unit surrounding a freezing chamber. The novel arrangement of baffles in an evaporator to provide the utmost in transfer of heat from the freezing chamber to the refrigerant, and to provide structural support of the freezing chamber walls is also an objective.

Still again, it is an object of this invention to teach extreme simplicity in construction and economy of manufacture, as will appear from the following specification and drawings, in which:

Fig. 1 is a front elevation of an ice refrigerator partially broken away, showing the quick-freeze unit therein.

Fig. 2 is a vertical cross section through the freezing chamber and the parts adjacent thereto; and

Fig. 3 is a perspective view, partially broken away, of the evaporator element.

Referring particularly to Fig. 1, the reference numeral 2 denotes the quick-freeze unit supported by brackets 4 in a refrigerator 6, which has an ice compartment 8. Ice in the refrigerator causes removal of a great amount of heat from the air surrounding the quick-freeze unit, and thus cooperates with the compressor 10 to provide an extremely low temperature in the freezer.

Compressor 10, mounted beneath the refrigerator, is belt-driven by electric motor 12 so that the refrigerating fluid is forced through condenser 14, receiving tank 16, and through supply pipe 18. Supply pipe 18 extends upwardly along the outer side of the rear wall of the refrigerator and passes inwardly through a suitable aperture, not shown, in the refrigerator wall. Inside the refrigerator, supply pipe 18 is connected to the inlet side of the evaporator unit, the outlet side of which is connected by suction return pipe 20 to the suction side of compressor 10.

Fig. 2 shows the specific elements of the quick-freeze unit 2 enclosed in the rectangular wooden casing 30. The rear wall of casing 30 is provided with an aperture 19 through which supply pipe 18 passes to expansion valve 22, which is nested in recess 23 hollowed out of the inner side of the rear wall of casing 30.

Expansion valve 22 is connected by pipe 24 to the evaporator, which is surrounded by insulat-

ing material 28, preferably formed of pressed cork, although obviously other materials would suffice.

As shown in Figs. 2 and 3, the evaporator is formed of outer and inner shells 32 and 34, respectively, of sheet metal. The shells are held in spaced relationship by thin, strip-metal baffles, designated A—A and B—B and the single baffle C—C, the side edge being preferably soldered to the shells. Baffles A—A and B—B are of substantially uniform length, and shorter than the shells so that alternate staggering thereof provides a continuous, single labyrinth passage between the inner and outer shells. Baffle C—C extends along the entire length of the shells to provide a uni-directional flow of refrigerant through the passage as will be more fully explained. The B—B baffle and the baffle C—C abut against the rear end wall 36 of the evaporator, to which they are soldered to provide a fluid tight seal. Rear end wall 36 is a rectangular sheet of metal soldered to the end edges of the inner and outer shells 34 and 32, and provided, on opposite sides of baffle C—C, with holes 38 and 40, at the outer sides of which outlet and inlet pipes 20 and 24 are soldered. The front end edges of the inner and outer shells, the baffle A and the baffle C are all soldered to the rectangular frame 42, which may be stamped of sheet metal, to enclose the evaporating chamber.

It is apparent that when refrigerating fluid enters the evaporator through hole 40, it must pass back and forth between the baffles as indicated by the arrows until it can reach the outlet 38. This, in effect, provides an extremely long evaporating chamber. Since the baffles are only in edge engagement with the surface of shell 34, the inner and outer surfaces of the shell are relatively unobstructed so that heat may transfer through the shell from the freezing chamber 36 to the expanding refrigerant in the evaporator.

As shown in Fig. 2, nuts 44 are soldered to the front face of frame 42 for engagement in countersunk recesses 45 in the rear edge of boards 48 which form a rectangular throat. Bolts 46 pass through the boards 48 threadedly to engage nuts 45. The planks 48 which form the throat are secured by screws (not shown) to front end member 50 of the casing, and the front opening of the casing is closed by tapered cork plug 52 which is faced by the rectangular wooden piece 53. A hollow rubber tube 54 is secured to the front wall of the casing to provide weatherstripping, thus insuring tight sealing of the food chamber 36 when engaged by facing piece 53.

It is apparent that the ice in the refrigerator cools the air surrounding the evaporator so that the major portion of the heat absorbed by the refrigerant in the evaporator comes from the food stored in the freezing compartment. Since the motor, compressor and condenser are outside the refrigerator, the heat given off thereby need not be absorbed in the refrigerator.

Since most of the component parts of this device may be readily formed of sheet material with simple cutting tools, and since the parts may be assembled without special jigs, forms, or dies, the units may be manufactured extremely easily and inexpensively.

15 The special arrangement of the shells and baffles combines structural rigidity with thermal efficiency in a device, the manufacture of which is well within the capabilities of any competent sheet metal worker after the teachings of this disclosure.

This invention is not to be limited to the elements shown and described, and all obvious modifications and equivalents are to be included within the scope of the following claims.

25 I claim:

1. An evaporator for a refrigerator, comprising spaced inner and outer shells of sheet material, end wall members engaged between the end portions of said shells for enclosing an evaporator chamber therebetween, a single, longitudinal baffle comprising a strip of material extending to each end wall and having the side edges thereof engaged with the respective surfaces of the shells, refrigerating fluid inlet and outlet means disposed on each side, respectively, of said baffle, two groups of substantially identical, longitudinal baffles formed of strips of material of a width substantially equal to the distance between the shells and of a length substantially shorter than said shells, the members of one group being disposed, successively, from each side of said single baffle at spaced intervals, the ends of said group abutting one end wall member, the individual members of the other group being disposed between each pair of the first-mentioned group and having their ends abutting the opposite end wall.

2. A quick-freeze refrigerator unit, including an inner shell of sheet metal providing top, bottom, and side walls of a food storage chamber and the inner wall of an evaporator chamber, an outer shell spaced from the inner shell and forming the outer wall of the evaporator cham-

ber, an end plate attached to the rear end portions of the shells for forming the rear wall of said chambers, a flat, frame-like member attached to the front portions of said shells for enclosing said evaporator chamber, and a plurality of substantially identical, longitudinally disposed baffles engaged between said shells, said baffles being shorter than said shells and being divided into two groups, the individual members of the first group being alternately spaced between the members of the second group, the end edges of the first group being engaged against said member, the end edges of the second group being engaged against said plate, whereby to support said shells in spaced relationship and whereby to provide an elongated passage for refrigerant, and inlet and outlet means for conducting refrigerant to and removing it from the passage.

3. In a quick-freeze refrigerator unit as claimed in claim 2; a layer of insulating material surrounding said outer shell, a casing substantially surrounding said insulating material, said casing having an opening in the front wall thereof for access to said food-storage chamber, support means engaged with said front wall and said flat, frame-like member for holding said shells rigid with respect to said casing, and closure means for closing said front opening.

4. In a quick-freezing refrigerator unit, an inner shell of sheet material forming the top, bottom and side walls of a food storage chamber, said inner shell forming the inner wall of an evaporator, the end walls of said evaporator being formed of sheet material joined to the end edge portions of said inner shell and extending substantially outwardly therefrom, a plurality of strips of sheet material spaced from one another having one longitudinal edge secured to the outer side of said shell, and having one end edge secured to one end wall of said evaporator, the other end edge of each of said strips having at least a portion thereof spaced from the other end wall of said evaporator, the outer wall of said evaporator comprising an outer shell formed of sheet material joined to the other longitudinal edges of said strips, said outer shell having the end edge portions thereof secured to said end walls, and inlet and outlet means for conducting refrigerant to and removing it from said evaporator.

WALTER S. PHILLIPS.
